Primary Examiner — Cynthia R Underwood*(74) Attorney, Agent, or Firm* — Greenberg Traurig, LLP(57) **CLAIM**

We claim the ornamental design for a nut, as shown and described.

DESCRIPTION

FIG. 1 is a front projected isometric view of a nut;
FIG. 2 is a back projected isometric view of FIG. 1;
FIG. 3 is a front orthogonal view of FIG. 1;
FIG. 4 is a back orthogonal view of FIG. 1;
FIG. 5 is a left side view of FIG. 1;
FIG. 6 is a right side view of FIG. 1;
FIG. 7 is a top view of FIG. 1; and,
FIG. 8 is a bottom view of FIG. 1.

1 Claim, 6 Drawing Sheets---
